U.S. Cl. D9—193

Published under the second Trial Voluntary Protest
Program on Apr. 6, 1976 as document No. B237975

FIG-1

FIG-5

FIG. 1 is a perspective view of a package of label rolls showing my new design;

FIG. 2 is a top plan view;

FIG. 3 is an elevational view of the end opposite that seen in FIG. 1;

FIG. 4 is an elevational view of the side opposite that seen in FIG. 1; and

FIG. 5 is a bottom plan view thereof.

I claim:

The ornamental design of a package of label rolls, substantially as shown.
